ATTORNEY.

UNITED STATES PATENT OFFICE.

GEORGE L. WITSIL, OF PHILADELPHIA, PENNSYLVANIA, ASSIGNOR TO
EDWARD REEVE AND THOS. L. BATES, OF SAME PLACE.

CARPET, PAD, AND MAT.

SPECIFICATION forming part of Letters Patent No. 239,908, dated April 5, 1881.

Application filed May 17, 1880. (No specimens.)

To all whom it may concern:

Be it known that I, GEORGE L. WITSIL, a citizen of the United States, residing in the city and county of Philadelphia, and State of Pennsylvania, have invented a new and useful Improvement in Carpets, Pads, and Mats, which improvement is fully set forth in the following specification and accompanying drawings, in which—

10 Figures 1 and 2 are views of opposite faces of the carpet, &c., embodying my invention. Fig. 3 is a side elevation, showing the application of the article to stairs.

15 Similar letters of reference indicate corresponding parts in the several figures.

My invention consists of a carpet, pad, or mat formed of layers or pieces of sponge interposed between facings of suitable fabric, thus forming a soft and durable covering which 20 is tufted at intervals with metallic fastenings for strengthening purposes, and especially adapting the covering for stairs.

25 Referring to the drawings, A represents a piece of carpet, a pad, or mat formed of facings a, of cotton, linen, woolen, or other fabric, between which is interposed a layer, b, of sponge.

30 c represents tufting, which may be of the form of rivets and burrs, the rivets being passed through the facings and sponge and properly headed, or of strips of metal on one facing, and rods or wires on the other facing, the strips being perforated to receive the ends of the rods or wires, which are passed through

the facings and sponge and clinched on the strips.

35 It will be seen that I form a thick and soft carpet, &c., which is strengthened by the tufting, and thus made durable. Should there be moisture in the apartment, or on the floor where the carpet, &c., is laid, the sponge absorbs the moisture through the facings. As 40 the tuftings are located at intervals I produce admirable coverings for stairs, as the carpets and pads may be bent to conform to the angular shapes of stairs, and secured in position 45 by tacking at the corners, thus dispensing with stair-rods, if so desired. The sponge is preferably in small pieces, and the tuftings form pockets therefor and prevent shifting thereof, whereby uniform surfaces for the carpet, &c., 50 are maintained.

I am aware that it is not new to form carpets and pads of fabric with an inclosure or lining of sponge and tufting the same, and therefore disclaim such features.

55 Having thus described my invention, what I claim as new, and desire to secure by Letters Patent, is—

The carpet, &c., formed of fabric-facings a, sponge-layer b, and metallic tufting c, substantially as and for the purpose set forth.

GEO. L. WITSIL.
